UNITED STATES PATENT OFFICE.

FREDERICK W. ERSFELD, OF NEW YORK, N. Y.

SHOULDER-SUPPORT FOR PERSONAL WEAR.

1,112,201.

Specification of Letters Patent.

Patented Sept. 29, 1914.

Application filed March 23, 1914. Serial No. 826,485.

To all whom it may concern:

Be it known that I, FREDERICK W. ERSFELD, a citizen of the United States, and a resident of the borough of Bronx, city, 5 county, and State of New York, have invented certain new and useful Improvements in Shoulder-Supports for Personal Wear, of which the following is a specification.

10 The object of my invention is to afford comfortable but nevertheless effective means whereby the shoulders of the wearer may be trained and sustained yieldably to assuming the "square" upright carriage which is 15 so conducive to health and symmetrical appearance;—in other words to counteract and overcome the tendency to droop, or the forward inclination so prevalent with a majority of individuals lacking in physical 20 training and exercise. Furthermore as a corollary the object is to increase the lung power or breathing capacity of the user by expanding the chest and insuring an upright posture and bearing of the body generally, 25 it being well known that when the shoulders are habitually thrown back squarely the tendency is to straighten and improve the appearance and health of the whole physical structure.

30 The invention resides in the novel construction and arrangement of parts hereinafter more fully described and claimed.

In the accompanying drawings, Figures 1, and 2, are front and rear views of the upper 35 portion of a person wearing my shoulder supports; Fig. 3, a view of the supports and suspender straps, unattached; Fig. 4, a detail view of the under side of one of the cushion pockets; Fig. 5, a cross section 40 upon line 5—5 Fig. 4; Fig. 6, a longitudinal section of one of the bulbous cushions.

In carrying out my invention and discovery practically I have heretofore found bulbous rubber cushions of ovoidal shape the 45 most desirable form of elastic resilient arm pit cushion, since they may be made of light weight, and are delicate and sensitive to pressure, while affording the requisite degree of resistant tendency to the lowering 50 or drooping of the shoulders. The bulbous cushions are preferable in many respects in that they may be made of any size, shape, and strength of resilient power with a minimum of weight. They are further- 55 more non-absorbent and cool, and practically indestructible for the purpose design-

nated, and may be manufactured cheaply to meet the requirements of all possible users.

The cushions *a*, when made of rubber or 60 similar elastic material preferably have one or more vent holes *a'*, to admit of the displacement and reentrance of air as the bulb or cushion is compressed and then released, in whole or in part,—the air when confined 65 or sealed within the bulb having a tendency to stiffen the cushion more than is desirable for the ordinary use of delicate or young persons, whereas when the air is allowed to fluctuate in and out of the cushion it makes 70 the cushion more delicate and quickly responsive to both increased and relaxed pressure.

In order to sustain my elastic resilient 75 cushions *a*, in position under the shoulders of the wearer, and within the arm pits, I attach them to any suitable form of flexible 80 suspenders *B*, as may be found most expedient, those shown in the drawings having been found effective in use, but being capable 85 of change or modification as may be found most expedient in adapting the device to the varying requirements of use on persons of different age, size or sex. Hence I do not confine myself necessarily 90 to the identical form and arrangement of straps and suspenders shown, in which *b*, may be designated as the cushion belt carrying the elastic resilient cushions *a*, *a*, and *b'*, *b'*, as the shoulder straps 95 for sustaining the cushion belt *b*, in position. The cushion belt *b*, is provided with a buckle *c*, or other well known means for adjustably securing its ends together; and the front portions of the shoulder straps *b'*, *b'*, are formed with adjustable loops *b**, *b**, having sliding buckles *c'*, *c'*, like unto those for instance used on suspenders for under garments.

A convenient means of sustaining the 100 elastic resilient cushions *a*, *a*, in position is to confine them within pockets *p*, *p*, secured to the cushion belt *b*, and provided with closure means *p'*, such as "glove button" fastenings or any other button or equivalent 105 form of fastening that will admit of the insertion or removal of the cushions for purpose of cleaning, &c.

Furthermore, the device is simple and cheap as well as efficient, and can by no 110 possibility result in injury to the wearer.

In the case of persons with shoulders of

unequal height the cushions are made of different sizes to remedy the defect; and when a cure is effected, the use of the cushions may of course be discontinued.

5. What I claim as my invention and desire to secure by Letters Patent is,

1. As an improved article of manufacture for personal wear, a shoulder-sustaining device comprising inflatable bulbous elastic 10 cushions, a belt to which said cushions are secured and shoulder straps connected with said belt at the back and having loops slidably engaging said belt at the front.

2. As an improved article of manufacture 15 for personal wear, a shoulder-sustaining device comprising inflatable bulbous elastic cushions, a belt having pockets in which

said cushions are retained, closures for said pockets, and shoulder straps connected with said belt at the back and front.

20

3. As an improved article of manufacture for personal wear, a shoulder-sustaining device comprising inflatable bulbous elastic cushions, a belt having pockets in which said cushions are retained, closures for said pockets, shoulder straps connected with said belt at the back and front, and said closures for said pockets being detachably held in closed position.
